FIG. 1

Des. 189,971

PAGE 2

FIG. 2

FIG. 1

Figure 1 is a front perspective view of a combined television magnetic tape recorder and reproducer incorporating my new design;

Figure 2 is a side elevational view of Figure 1, the opposite side being substantially a mirror image of the side shown; and

Figure 3 is a rear elevational view.

Diagonal lines are used to indicate transparency of material.

The top and bottom views are conventionally plain. I claim:

The ornamental design for a combined television magnetic tape recorder and reproducer, substantially as shown and described.
